UNITED STATES PATENT OFFICE.

EUGENE L. MILLER, OF PORTLAND, OREGON.

SYSTEM OF CLOSET SANITATION.

1,081,130.

Specification of Letters Patent.

Patented Dec. 9, 1913.

Application filed May 28, 1913. Serial No. 770,281.

To all whom it may concern:

Be it known that I, EUGENE L. MILLER, a citizen of the United States, residing at Portland, in the county of Multnomah and State of Oregon, have invented new and useful Improvements in Systems of Closet Sanitation, of which the following is a specification.

This invention relates to a closet, and has particular reference to improved means for making such closet sanitary, odorless, and convenient of operation.

To this end the object of the invention is to provide a structure comprising a closet removably mounted on a decomposing tank or vault, and to introduce in such tank conveniently operated means for tightly closing the entrance to said tank.

A further object is the provision of means, removably fixed in said tank, for receiving the sediments gathering without disturbing the flow of the decomposing liquids in the tank.

The objects and advantages of my invention are readily comprehended by referring to the following description and to the accompanying drawings, of which:

Figure 1 is a side elevation, partly in section, of a structure embodying the invention, Fig. 2 is a view on a larger scale of the main portions of the structure and modified operating means for the shutter, and Figs. 3, 4 and 5 illustrate details of construction, the functions of which are herein-after fully explained.

The reference numeral 1 denotes a closet, and said closet is at the top fitted with a seat and cover mechanism 2, and with a vent pipe 3. The bottom of said closet is made with a flange 4, which projects through the flooring 5. Below said flooring is a tank 6 for holding the fluid chemicals employed for decomposing and deodorizing purposes. Said tank has an overflow pipe 7, the entrance to which is conveniently covered by a suitable screen 8, said screen provided for the purpose of preventing solids leaving the tank. The tank is near the bottom made with a suitable drain 9, through which the contents of the tank may be emptied when required. In Fig. 2 is shown a common plug for closing said drain, but I wish it understood that a stop cock or similar device, having the same function, may be substituted. Thus by referring to Fig. 1 it is noticed that the overflow pipe and the drain

pipe extend to an overflow vault, and that said drain pipe is provided with a suitable stop cock.

Between the closet flange 4 and the flooring 5 is interposed a flanged rim 10, which forms the top portion of the sediment receiving means above mentioned. The bottom of said means takes the shape of a low vessel 11, and said top and bottom portions are combined by a screen 12 to form a screened basket or receptacle in which the sediments are free to settle. Said screen is fixed on the bottom in any suitable manner, as by providing a series of perforations 13 in the bottom 11, and by running a wire through said perforations and the meshes of the screen, as well known to the art.

As the receptacle should rest on the bottom of the tank 6 in order to avoid unnecessary strain on the former, and as the height of the tank is apt to vary, it is necessary to provide adjustment in fitting the screen on the rim 10. This may be accomplished by perforating said rim in the manner the bottom 11 is perforated, and by threading a wire through the perforations in the same fashion, or a series of projections or buttons 14 may be fixed in said perforations, which buttons are then readily caused to seat in the meshes of the screen after the receptacle is placed. It is obvious that such buttons can also be fixed in the perforations 13 of the bottom 11, so as to facilitate the connection and disconnection of the parts.

The deposits in the liquid within the receptacle stay there until dissolved or decomposed, whereupon they pass through the overflow pipe 7 and out of the building to the overflow vault shown in Fig. 1. In the course of time, no matter how well the decomposing liquid performs its function, sediments will settle in the bottom of the receptacle. In a long space of time a quantity of such sediments will have gathered, and the receptacle should be cleaned out. This operation is readily performed by removing the closet and by lifting the receptacle out of the tank, by placing said receptacle in a tub, and by carrying it out of the house, whereupon it can readily be cleaned, and the parts are easily separated in order to facilitate such cleaning. The objection to a structure of this kind is the unsightliness of the surface of the liquids and solids in the tank, as disclosed through the closet, the splashing caused by matters dropping

into said liquids, and the temporary odors rising through the closet. In order to overcome such objections a false bottom or shutter 15 is mounted in the receptacle. This 5 shutter is conveniently shaped to resemble a low bowl, substantially as shown, in order that the matter dropping into the closed shutter may seek the center. Said shutter, when closed, takes a position directly above 10 the surface of the liquids in the tank, substantially as indicated in the drawings, and as it is fitted within the rim 10, it forms an air tight bottom for the closet. This shutter comprises two halves 15^a, 15^b, pivotally 15 fixed on the rim 10 of the receptacle. After using, this shutter is opened by depressing the shutter leaves, as illustrated, whereby said leaves dip into the decomposing liquid and become thoroughly cleaned. The 20 mechanism for operating said shutter should extend above the tank to a point within easy reach of the person using the closet, and such mechanism may conveniently take the form illustrated in Figs. 1 25 and 2.

At one side of the closet, and on the flange of the rim 10, is mounted a standard 16, in which is pivotally hung an operating lever 17, said lever having an integral arm 30 17^a, from which extend connecting links 18, 19 to the shutter leaves. A coil-spring 20 is placed between said arm 17^a and the foot of the standard 16 for the purpose of yieldingly retaining the shutter in closed position.

In Fig. 3 is shown a modification of the operating handle. In this case the link 19^a is pivoted on the link 18^a, and the latter is extended upwardly and fitted at the top 40 with a handle or grip 18^b. A coil spring 20^a encompasses said links, and the link 18^a is provided with suitable projections 18^c, against which said spring exerts its pressure. In this view the operating mechanism is shown depressed in order to illustrate the effect of such depression on the various parts. The said shutter mechanism may also be constructed as shown in Fig. 4. In this case a one-leaf shutter 21 is presented, and said shutter leaf has a center pivot 22, mounted to rotate in the rim 10^a. On one end of the pivot is fixed a pinion 23, which engages the internal teeth of a rack-frame 24. Said frame extends above 55 the flooring and is at the top made with a handle 25. By moving said rack frame up or down the shutter leaf is caused to rotate, thereby moving it quickly through the liquids in the tank, and cleaning it thoroughly.

Experience may suggest other and better shutter movements, and the above are presented in order to demonstrate that the shutter must form an air-tight joint and 60 must pass through the liquid below, in open-

ing and closing, in order to be thoroughly cleaned.

The advantages of my invention are now readily understood. The basket receptacle is easily removed and reinserted. The 70 shutter is mounted in the rim 10, it shuts out all odors, it prevents splashing, and it covers all unsightly matters. When the sediment receptacle must be cleaned, or in case of repairs, it can quickly be disconnected from the rim, and the latter reinserted, whereby the structure is still at service, and the screen 8 of the overflow pipe comes into use, by preventing matters not decomposed from leaving the tank. The tank 80 6 itself is also readily removed for repairs, as it is only necessary to disconnect the overflow and drain pipes, which operation, at the present state of the art, is quickly effected.

85.

I claim:

1. In a device of the class described, a tank arranged to receive excrement from a closet and adapted to contain a liquid chemical for decomposing purposes, an overflow duct for said tank, a receptacle disposed in the tank to contain deposits in the latter and comprising foraminous walls, a shutter normally closing the receiving portion of said receptacle and tank and movable into the liquid in the latter for the purpose described, and means for actuating said shutter accessible from a point exterior to the tank.

2. A decomposing tank open at the top, 100 said tank having an overflowing duct and drain at the bottom, and an opening to communicate with a closet, a shutter mechanism for said opening, and a spring-held handle lever rising at the side of the closet 105 for operating said shutter mechanism.

3. A decomposing tank open at the top, a receptacle fixed in said opening, said receptacle having screened sides and a cupshaped bottom, a shutter mechanism mounted in 110 said receptacle for the purpose of normally retaining said tank opening closed, and lever devices extending above said opening for operating said shutter.

4. A device of the character described, 115 comprising a tank adapted to contain a decomposing liquid, said tank having an overflow duct and a drain near the bottom and being adapted for connection with a closet, a screened receptacle in the tank, a shutter 120 mechanism pivotally fixed in said receptacle, a spring held hand lever above said tank, and connections intermediate the lever and said shutter mechanism.

5. In a device of the character described, 125 a tank containing decomposing liquids, said tank open at the top, a receptacle placed in said opening and reaching to the bottom of the tank, said receptacle having screens 130 adjustably fixed so as to vary the height.

- of the receptacle to suit the height of the tank, a shutter mechanism pivotally fixed in said receptacle, manually operated means for opening and closing said shutter, 5 said means extending above the tank and having a resilient member for normally retaining said shutter in closed position.
6. In combination, an open top tank, a receptacle placed in said tank and having a flange extending over the top of the tank, 10 said receptacle made with open work sides, an over flow duct in said tank, a spring-held shutter in said receptacle positioned directly above the surface of the liquid in the tank, and manually operated means for opening said shutter, said means extending above the tank so-as to be conveniently operated.
7. In a device of the character described, 20 a tank open at the top for communication with a closet, said tank having an overflow duct and a bottom drain for the liquids within the tank, a shutter for normally closing the tank, said shutter having the shape of a shallow bowl and comprising two 25 halves, and a spring held lever connected to deppress said shutter halves into the liquid within the tank, said lever extending above said tank so as to be conveniently operated.
- 30 8. In a device of the character described, a decomposing tank open at the top, a flanged rim in the tank opening, a shutter fixed to operate in said rim and normally forming an air-tight partition in the passage 35 through the rim, and manual means, operable from above the tank, for opening said shutter, said opening operation causing the shutter to pass through the liquid in the tank so as to thoroughly clean said shutter.
9. Improved means of the class described comprising in combination, a decomposing tank adapted to contain a liquid chemical and having an overflow outlet, an overflow vault connected with said outlet, a receptacle adapted to be connected with a closet and arranged in said tank and having walls so formed as to establish communication between the receptacle and tank so that the decomposed deposits in the receptacle may pass from the same into the tank, a closure 40 for said receptacle and comprising movable shutter members, and means for moving said shutter members to open the same and simultaneously immerse them in the liquid in the tank and comprising a handle operable from a point exterior to the tank, links having connection with said handle and with the shutter members, and spring means coöperating with the handle to normally hold the same in a position wherein the said 45 shutter members are closed.
- 55 10. In a device of the character described, the combination with a decomposing tank; of a screened receptacle for sediments placed in said tank; and means for tightly 50 closing said tank, said closing means fixed to operate within said receptacle and removable with the receptacle, said closing means operable from above the tank and so related as to pass through the liquids in the tank in 55 opening and closing.
- 60 In testimony whereof, I have hereunto affixed my signature.

EUGENE L. MILLER.
